CLAIM

The ornamental design for a lighting fixture, as shown and described.

DESCRIPTION

FIG. 1 is a perspective view showing a new design for a lighting fixture;

FIG. 2 is a bottom view of the lighting fixture of FIG. 1; FIG. 3 is a top view of the lighting fixture of FIG. 1; FIG. 4 is a left-side view of the lighting fixture of FIG. 1; FIG. 5 is a right-side view of the lighting fixture of FIG. 1; FIG. 6 is a front view of the lighting fixture of FIG. 1; and, FIG. 7 is a rear view of the lighting fixture of FIG. 1.

The dashed lines showing portions of the lighting fixture are included for the purpose of illustrating environment and form no part of the claimed design.

The symbolic break in the drawings is understood to represent a continuation of the design uniformly along a non-specified length. The appearance of any portion of the article between the break lines forms no part of the claimed design.
